MICROSTILL

John J. Piros, Homewood, Ill., and John A. Glover, Munster, Ind., assignors, by mesne assignments, to Sinclair Research Laboratories, Inc., Harvey, Ill., a corporation of Delaware

Application March 11, 1949, Serial No. 80,796

9 Claims. (Cl. 202—158)

1

This invention relates to an improved laboratory micro-still suitable for use in the precision fractionation of small volumes of mixtures of liquids having different boiling points.

Laboratory micro-stills for use in the analysis of small volumes of mixtures of liquids having different boiling points are known in the art, being described, for example, in *Svensk Kem. Tids.* 58, 145-150 (1946). Such stills, in addition to comprising a still pot for holding the charge, fractionating tube and condenser system, also comprise a rotatable element disposed within the fractionating tube to aid in the fractionation. While such stills are useful for their intended purpose, there is a need in the art for a laboratory micro-still of improved fractionating efficiency. It is the object of the present invention to supply that need.

The conventional stills of the type described have as their rotatable element a metallic band, and the object of the present invention is accomplished by replacing such metallic band by a flattened helical wire coil, preferably wound upon a metallic band to provide support for such coil. The flattened helical wire coil has transverse major and minor axes at a right angle to its longitudinal axis, its dimension on the transverse major axis greatly exceeding its dimension on the transverse minor axis, its dimension on the transverse major axis being less than the diameter of said fractionating tube. When such a coil is employed, it is believed that the improved fractionating efficiency is obtained by increasing the "wetted wall" effect upon the sides of the fractionating tube by producing "point" contacting or "wall ridges," instead of the "window wiping" effect produced by the spinning band of a conventional micro-still.

A specific and preferred form of micro-still constructed in accordance with the present invention comprises a relatively long, thin, glass, fractionating tube which is provided near its upper end with two condensers, one spaced above the other. The lower condenser is adapted to receive cooling fluid through the control of the flow of which the extent of the condensation effected in this primary condenser is regulated. The second condenser, located above the primary condenser, is a total or final condenser and is adapted to condense all of the vapor passing the first condenser and to deliver such condensed vapor into a take-

2 off line. The fractionating tube, from a short distance above its lower end which is connected to a still pot, up to slightly below the bottom of the primary condenser section, is provided with a flattened helical wire coil. This element is slightly smaller in diameter than the internal diameter of the fractionating tube and is connected at its upper end to a rotatable shaft which extends through the remainder of the fractionating tube, including the two condensing sections thereof, emerges from the upper end of the second condenser, and is connected to a variable speed electric motor. Rotation of this element produces a "wetted wall" effect within the fractionating tube, thus producing intimate contact between the up-rising vapors and the returning reflux on the column wall. Accurately controllable heating means are provided for supplying heat to the still pot, and the still pot and heating element assembly are enclosed within a vacuum flask which is removably seated at its upper end against the bottom of a second vacuum flask which substantially encloses the fractionating tube, both condensers, and the take-off line. To minimize radiated heat losses, this latter vacuum jacket is insulated up to the total condensing section, and heat is supplied to the jacket to compensate for heat lost therethrough, thus assuring adiabatic operation of the still.

30 By regulating the flow of cooling fluid through the primary condenser, the total boil-up within the fractionating tube may be condensed and returned as reflux through the fractionating tube. Also, by proper regulation of the cooling fluid flowing through the primary condenser, which may be determined by the indication of thermocouples located just below and just above the primary condensing chamber adjacent the fractionating tube, a portion of the boil-up vapors may be allowed to pass through the primary condenser, to be condensed by the final condenser from which the condensate is delivered to the take-off line. In this manner the reflux ratio may be accurately controlled and regulated to any desired value. This arrangement additionally provides for automatic indication of the end of the fractionation of one component, since the take-off rate decreases and the reflux ratio increases as the fractionation of one component approaches the end point. Also, the primary condenser must heat up to the vaporization tempera-

ture of the succeeding component before additional vapor will pass through the primary condenser.

These features and advantages are made more apparent by the following detailed description, taken in conjunction with the accompanying drawings, in which:

Fig. 1 shows one embodiment of a micro-still in vertical section according to this invention;

Figs. 2 and 3 show another embodiment of a micro-still according to this invention;

Fig. 2 being the upper vertical section and Fig. 3 being the lower vertical section;

Fig. 4 is an enlarged front view of the unsupported helical wire coil employed in the still shown in Fig. 1;

Fig. 5 is a side view of the coil shown in Fig. 4;

Fig. 6 is an enlarged front view of the supported helical wire coil employed in the still shown in Figs. 2 and 3; and

Fig. 7 is a side view of the coil shown in Fig. 6.

In the micro-still of Fig. 1, the fractionating column consists of a thin glass tube 1, having an internal diameter, e. g. of about 3 mm., more or less, and an active fractionating length, e. g. of around 40 cm. The upper portion of the tube is equipped with two condensers, a primary or partial condenser 2 and a final or total condenser 3. The primary condenser is formed integrally with the fractionating tube and its internal cross-section area is larger than the fractionating tube to provide space for a thermowell 4. A chamber 1a, which extends from the fractionating tube 1 and is closed at its upper end, surrounds the thermowell 4 adjacent the primary condenser so that the thermocouples for measuring the temperature within this condenser are exposed indirectly on all sides to the vapor. The portion of the thermowell adjacent the primary condenser is adapted to accommodate two thermocouples 5 and 6 for indicating respectively the vapor temperature just below and just above this condenser. Suitable connections 7 and 8 are provided for supplying cooling fluid to the condenser.

The fractionating tube extends above the primary condenser and terminates around the total condenser 3 which is illustrated as a cold finger type condenser. This condenser is provided with entrance and exit connectors 10 and 11 for supplying cooling fluid thereto. The lower wall portions of condenser 3 are formed and sloped to drain all vapor condensing thereon onto a dripper 12 which is formed integrally with the condenser. The dripper is arranged to drip condensate therefrom into a take-off line 14, formed integrally with the fractionating tube.

A pear-shaped still pot 16 having a capacity, e. g. of about 10 cc., and provided with a thermowell 17 is removably connected to the bottom of the fractionating column, and heat is supplied thereto by a radiant heater 18.

The heater consists of a glass form 19 within which a Nichrome wire heating coil 20 is supported. A voltage regulator (not shown) is used to control a fluctuating input voltage to give a constant 115 volts output, and a reducing transformer (not shown), connected to the output of the voltage regulator, supplies a voltage of about 30 volts to the heating coil.

Heater 18 is resiliently supported against the bottom of pot 16 by a spring 22 which surrounds a projection 23 of form 19, and the lower end of the spring rests on the vacuum jacket 24 which may be internally silvered and which encloses the entire still pot and heater assembly. A transit

disk 25 disposed within the vacuum jacket assists in positioning the spring therein. A strip of the jacket may be left unsilvered to permit the still pot and the end of the fractionating tube to be observed.

In place of stationary packing employed in fractionating columns, the column of this improved micro-still is provided with a flattened helical coil 26, made of two No. 32 Nichrome wires wound at single wire width spacing to give a flattened double wire coil one mm. thick and of slightly less diameter than the internal diameter of the fractionating tube. For example, if the internal diameter of the fractionating tube is 2.75 mm., the diameter of the helical coil may be 2.7 mm. When larger diameter tubes are employed the diameter of the coil may be increased accordingly, if desired.

Coil 26 extends through the tube 1 for a length of approximately 40 cm. from a short distance above the still pot 16 to just below the lower end of the primary condenser section. The upper end of the coil is connected, e. g., silver soldered, to a length of thin tungsten rod 27. This rod passes through the upper sections of the fractionating tube, including the condensing sections, and through an opening 9 formed in the total condenser as a restricted extension of the fractionating column. Complete condensation of vapors entering this restricted opening is assured by virtue of the condensing surfaces provided on the total condenser adjacent such opening.

The upper end of rod 27 is adapted to be connected to the chuck of a variable speed electric motor. Rotation of coil 26 through rod 27 produces a "wetted wall" effect within the fractionating tube, thereby providing high fractionating efficiency in the small size columns described. The enlargement 13 of the restricted opening 9 in condenser 3 provides for flow of the condensate, which is formed within the restricted opening, down along the sides of the condenser rather than down the shaft 27, thereby minimizing the return to the still pot of vapors condensed within restricted opening 9.

The fractionating tube, the entire partial condenser, the chamber within which most of the total condenser is positioned, and the take-off line are enclosed within an integral vacuum jacket 30 which may be silvered internally up to the total condensing zone to minimize radiated heat losses. The channel for thermowell 4 extends through the wall of jacket 30 near the upper end thereof.

In order to assure adiabatic fractionation conditions throughout the column and in order to provide for the same linear expansion in the jacket as in the fractionating tube, jacket 30 is insulated and heat is supplied thereto. To this end an exploring thermowell 31 is positioned adjacent the surface of the jacket and the thermowell and jacket are wrapped together in a layer of glass cloth tape 32. A suitable length, e. g., about 20 feet, of Nichrome heating ribbon 33 is uniformly wound over the tape and a layer of glass wool 34 about $\frac{1}{2}$ inch in thickness is wrapped over the ribbon. The entire assembly is then wound with an external layer of glass cloth tape 35. The terminals of the Nichrome ribbon may be connected to a normal voltage source such as about 120 volts through a reducing and regulating transformer.

Any suitable receiver may be employed for collecting the condensate from the take-off line. In the still illustrated, a graduated pipette 38 is removably connected to the portion of the vacuum jacket surrounding the end of line 14. A glass

tube 39 provided with a neoprene stopper 40 is clamped to the stem of the pipette so that the stopper seals the bottom of the pipette. When the desired fraction or any part thereof has been distilled over into pipette 38, the clamp which holds tube 39 may be loosened, thus allowing the material which has accumulated in the pipette to drain into the tube, and another tube may be clamped in place immediately. If cuts of the distillate are not required, a Mohr type pipette which is heat sealed at its lower end, may be arranged to collect the condensate delivered through line 14. Water may be employed effectively as the cooling medium in the total condenser when fractionating liquids having boiling points in excess of the temperature of the water. In fractionating more volatile liquids, e. g. those having boiling points lower than the normal temperature of the water, it may be precooled, or other cooling fluids may be employed and may be precooled if desired. Air is a suitable cooling medium for use in the primary condenser when fractionating liquids having boiling points in excess of the temperature of the air employed. The air advantageously is supplied through a control valve from a constant-pressure source, and it may be precooled, if desired, depending on the condensation temperature of the liquids being fractionated. When fractionating more volatile liquids, other cooling fluids precooled, if desired, may be utilized in the primary condenser. Measurement of the quantity and speed of the cooling fluid passing through the primary condenser may be indicated by the use of a standard flowmeter.

In the operation of the still illustrated, the charge measured volumetrically or gravimetrically, is placed in the still pot 16, the pot is connected to the fractionating tube 1, current is supplied to heater 18, and the boil-up rate is adjusted to the desired value, e. g., about ten drops per minute run-back. While thus adjusting the boil-up rate by varying the heat input to the pot, sufficient air or other suitable cooling fluid is passed through the jacket of primary condenser 2 to condense all the up-rising vapors, coil 26 having been put into rotation upon evidence of boiling in the pot. The true overhead vapor temperature is indicated by thermocouple 5, this thermocouple being positioned at the lowermost end of thermowell 4, which end may be located, e. g., about 10 mm. above the top of rotating coil and about 10 mm. below the bottom of the jacket of the primary condenser. After the desired boil-up rate has been established and the vapor temperature above coil 26 has come to equilibrium, the rate of flow of cooling medium through the jacket of condenser 2 is gradually reduced until thermocouple 6 indicates that vapor is passing through this condenser. Sufficient cooling fluid passes through the jacket of cold finger condenser 3 to condense all vapor passing the primary condenser. By further regulation of the flow of cooling fluid through the primary condenser, the desired overhead take-off rate may be established, the indication of thermocouple 6 serving as a guide in effecting this regulation. The pot heat input is increased during the course of the fractionation to maintain the required quantity of boil-up. The current supplied to the heating element 33 of vacuum jacket 30 is controlled to maintain a minimum temperature difference between it and the vapor temperature. Fractions or cuts of fractions of the material being distilled may be removed periodically by changing the col-

lection tube 39 or other receiver as previously described.

The provision of the primary condenser, in combination with the final cold finger condenser, not only enables equilibrium conditions to be established within the column before take-off condensation is started, but also enables predetermined and accurate control of the take-off rate. In this manner any desired reflux ratio may be achieved. Also, use of the primary condenser to control the reflux ratio provides an automatic indication of the end of the fractionation of one component, since the take-off rate will decrease and the reflux ratio will increase at this end point and since the primary condenser must heat up to the vaporization temperature of the succeeding component before vapor thereof will pass by this condenser.

Columns such as that illustrated in Fig. 1 have been tested with binary mixtures of methylcyclohexane and 2,2,4-trimethylpentane and have demonstrated considerably higher fractionating efficiencies than are known to have been obtainable heretofore in laboratory micro-stills. For a column provided with a fractionating tube having an internal diameter of 2.75 mm. and with a rotating element of 2.7 mm. diameter, and utilizing rotating element speeds varying from about 1860 R. P. M. to about 2260 R. P. M., the theoretical plate value efficiencies were determined to range from about 130 to about 100 with boil-up rates varying respectively from about 0.07 ml. per minute to about 0.20 ml. per minute. Results obtained during routine fractionations in columns of the present invention provided with fractionating tubes having internal diameters ranging from 2.80 mm. up to 3.10 mm. and with rotating elements having a diameter of 2.7 mm., have shown no marked differences when compared with a column provided with a fractionating tube having an internal diameter of 2.75 mm. and with a rotating element having a diameter of 2.7 mm.

An embodiment of the apparatus of the present invention may also be used in vacuum fractionation if means are provided for the transmission into the evacuated space of the mechanical power required to rotate the helical coil. Such means may be a conventional packing, such as is described in the aforementioned Svensk Kem. Tids. reference, but is preferably that described in the John J. Piros application entitled "Non-Leaking Rotary Seal," Serial No. 80,795, filed of even date herewith and issued as Patent No. 2,560,660. Figs. 2 and 3 of the drawings illustrate such an apparatus.

In Figs. 2 and 3, the fractionating column consists of a 10 mm. heavy-wall Pyrex glass tube 41 having an internal diameter of 5.9-6.0 mm. and having a length of about 60 cm. Above the tube are two condensers, a primary or partial condenser 42 and a final or total condenser 43.

The partial condenser's purpose is to provide the required reflux for column operation by condensing a part of the boil-up. By regulating the rate of air passing through this condenser, using connections 44 and 45, the amount of vapors allowed to get past the partial condenser to the total condenser above it is controlled. The partial condenser has an opening through its entire length which allows a rotating tungsten shaft 46 to pass through it and extend into the rotating part of the rotary seal where it is held in place by a small set screw 47. The total condenser is a double helical coil through which the cooling medium, water or air, passes, the cooling medium

being supplied using connections 48 and 49. The double helical coils are joined at the bottom and at their junction a dripper 50 is placed so as to cause the material draining from the condenser coils to drain to the take-off line 51. The thermowell 52 enters near the top of the vacuum jacket 53 and passes through the vacuum jacket and into the vapor zone at a point just below the lower end of the partial condenser. The length of the thermowell within the vapor zone is 30 mm. The end of the thermowell is about 5 mm. above the glass tube 41.

Compressed air is used as the cooling medium in the partial condenser. Since the compressed air pressure fluctuates somewhat, it is reduced to 20 lb. per sq. in. before going to a small needle valve (not shown) by which the air going to the partial condenser is regulated. A "Fisher and Porter Flowlator" with a hollow aluminum float in a 2B tube (not shown) is used to measure the air coming from the partial condenser. Water or air may be used as the coolant for the total condenser. In the case of this condenser the coolant rate does not have to be regulated but should be kept sufficiently high to prevent any vapors from by-passing it.

A Mohr type pipette 54, sealed off at its bottom graduation, is used as a receiver during fractionations which do not require cuts of the overhead material to be taken. If cuts are to be taken during vacuum operation, a small turntable type fraction cutter is used.

The fractionating section, the condensing section and the take-off line are enclosed in an integral vacuum jacket 53. To minimize radiation losses the entire vacuum jacket is silvered, with the exception of the take-off line. The take-off line is left unsilvered so that when materials such as waxes and naphthalenes are distilled they may be kept liquid in the take-off line by directing heat from an infrared lamp on the take-off line. To minimize the radiation losses from the silvered vacuum jacket an external heater 55 is placed around the jacket. The column is prepared for winding with Nichrome ribbon by placing into position next to the jacket 56 an exploring thermowell and then wrapping the jacket with a single layer of glass cloth tape. Over this tape, Nichrome ribbon of the proper length and size to give about 250 watts maximum output is uniformly wound. A $\frac{1}{2}$ " layer of glass wool is wrapped over the ribbon and the entire heater section is wound with another layer of glass cloth tape.

The column is provided with a round-bottomed cylindrical pot 57 having a total capacity of about 80 ml. This long form of a pot is used so as to allow a disengaging space above the boiling liquid. Materials boiling under vacuum often have a tendency to bounce and froth and thus might flood up into the column if a shorter pot were used. To promote boiling in the pot powdered glass 58 is fused to the bottom. There is a thermowell 59 located in the pot. The dripper 60 which returns the run-back from the column is located above the standard taper to which the pot is attached. Heat is supplied to the pot by a small radiant heater 61 made of six feet of #28 Nichrome wire. The glass form 62 which holds the Nichrome coil of the radiant heater is held against the bottom of the pot 57 by a spring 63 which rests on the bottom of a strip silvered one-quart Dewar flask 64 which encloses the entire pot assembly. The spring is held centrally in the bottom of the Dewar by a holder 65 which slips into the flask.

Since in a micro-sized column it is especially

important to maintain a constancy of heat input to the column, a regulated 115-volt supply is used. For use in the pot heater the regulated voltage is reduced to 30 volts by a Variac. This reduced voltage is further controlled by another Variac through which the voltage to the pot heater can be regulated from 0-30 volts. The jacket heater is connected to the regulated 115-volt supply by a Variac. These details are not shown in the drawings.

In place of the conventional spinning band, the column of this improved vacuum micro-still is provided with a flattened helical coil 66 made of two #28 Nichrome wires wound at single space width spacing to give a flattened double wire coil about 5.7 mm. in width and 1.5 mm. in thickness. The coil has strung through its entire length, about 60 cm., a Nichrome ribbon 61, $\frac{1}{8}$ in. wide and 0.007 in. thick. The coil is silver soldered to the ribbon at both ends. The upper end of the Nichrome ribbon extends 5 mm. beyond the top turn of the flattened coil and is doubled back over its last 3 mm. to form a hook by which the packing can be attached to a flat-bottomed loop which is silver soldered to the lower end of the rotating 1.6 mm. tungsten shaft 46 which passes through the partial condenser.

To provide for linear expansion or contraction of the fractionating tube within the vacuum jacket, due to differences in temperatures between the pieces, a double helical coil 68 of 7 mm. outside diameter Pyrex is placed at the bottom of the fractionating tube.

The desired rotation of the tungsten shaft 46 is effected by means of the rotary seal positioned at the top of the micro-still. Such rotary seal comprises a stationary member 69 attached to the evacuated space by means of a rubber tube 70. If desired, the bottom portion of the stationary member may be made with a standard taper machined on it so as to facilitate its insertion into a glass taper. This stationary member is made of "Teflon" (tetrafluoroethylene polymer) bar stock.

The numeral 71 represents a rotatable member of the rotary seal, machined from cold rolled steel.

A straight piece of steel rod 72 is silver soldered to the top of rotatable member 71, and a spring 73 is positioned between the member 71 and a sleeve 74, being soldered to both of them. The sleeve is attached to the chuck of the stirring motor.

A small set screw 75 is provided to attach to the rotating member 71 the tungsten shaft 46. The set screw is sealed over with high temperature cement during operation.

After the charge is placed into the pot 57 and the pot assembly and receiver are put in place, the pressure is reduced. A cartesian diver type or other suitable type of manostat can be used to control the pressure during vacuum operation. However, it has been found possible to dispense with the use of the manostat when thermally stable compounds are distilled by connecting to the still a large surge bottle which has been pumped down to the operating pressure along with the still. If the rotary seal has been properly assembled and precautions taken to prevent leaks in other parts of the system, the entire distillation can be run off without further use of a vacuum pump or a manostat.

After the pressure is adjusted to the desired operating level, heat is put into the pot and the boil-up is adjusted to the proper rate of about 30 to 50 ml. per hour runback. During the time

the boil-up rate is being adjusted sufficient air is passed through the partial condenser to condense totally the boil-up. The rotating packing is turned on when there is evidence of boiling in the pot. After the proper boil-up rate has been established and the vapor temperature above the packing has come to equilibrium, the air rate through the partial condenser is slowly cut back until the desired overhead take-off rate is reached.

When tested, the vacuum still described successfully handled charges of 5-40 ml., operating at pressures from atmospheric to less than one mm. of mercury absolute and at temperatures from room temperature to over 500° F. at the head. Using dibutyl phthalate the hold-up was found to be between 0.5-0.7 ml. at normal boil-up rates and at one mm. of mercury absolute head pressure. The normal boil-up rate ranged from 40-120 ml. of liquid per hour, and for efficient fractionation, the take-off rate was held below two ml. per hour. At total reflux and at 40 ml. of liquid per hour boil-up, the column tested at 55-60 theoretical plates at atmospheric pressure, and at one mm. of mercury absolute pressure with a 60 ml. of liquid per hour boil-up and take-off rate of 0.40 ml. per hour the column had an efficiency of about 20 theoretical plates. At a 40 ml. of liquid per hour boil-up rate of dibutyl phthalate at one mm. of mercury at the head, the pressure drop through the column was 1.5 mm. of mercury.

This application is a continuation-in-part of our copending application entitled "Microstill," Serial No. 721,656, filed January 11, 1947.

We claim:

1. A laboratory micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, a condenser associated with said tube disposed above said coil and a take-off line for removing condensed vapors.

2. A laboratory vacuum micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, means including a seal for rotating said coil, a condenser associated with said tube disposed above said coil and a take-off line for removing condensed vapors.

3. A laboratory micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, band means mounted within said coil for the support thereof, a condenser associated with said tube disposed above

said coil and a take-off line for removing condensed vapors.

4. A laboratory vacuum micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, band means mounted within said coil for the support thereof, means including a seal for rotating said coil, a condenser associated with said tube disposed above said coil and a take-off line for removing condensed vapors.

5. A laboratory micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, band means mounted within said coil for the support thereof, a primary condenser associated with said tube disposed above said rotatable coil and arranged to return all vapor condensed thereby as reflux, a take-off line, a total condenser disposed above said primary condenser and arranged to deliver all vapor condensed thereby to said take-off line, and means for rotating said coil within said tube.

6. A laboratory micro-still as defined in claim 5, including an integral vacuum jacket substantially enclosing said fractionating tube, primary condenser, total condenser and take-off line, said jacket being silvered internally with the exception of that part thereof surrounding said take-off line.

7. A laboratory micro-still as defined in claim 5, including an integral vacuum jacket substantially enclosing said fractionating tube, primary condenser, total condenser and take-off line, and a thermowell entering said vacuum jacket near the top thereof and passing through said jacket and into the vapor zone at a point below the end of the primary condenser.

8. A laboratory micro-still for the fractional distillation of small quantities of mixtures of liquids having different boiling points, comprising a still pot, a fractionating tube connected thereto, a rotatable elongated helical wire coil disposed within said tube and having transverse major and minor axes, its dimension on the transverse major axis greatly exceeding its dimension on the transverse minor axis, its dimension on the transverse major axis being less than the diameter of said fractionating tube, band means mounted within said coil for the support thereof, a primary condenser associated with said tube disposed above said rotatable coil and arranged to return all vapor condensed thereby as reflux, a take-off line, a total condenser disposed above said primary condenser and arranged to deliver all vapor condensed thereby to said take-off line, and a rotatable shaft extending through an opening through the entire length of said primary condenser, said shaft being connected to said rotatable coil.

11

9. A laboratory micro-still as defined in claim 8, in which said total condenser is formed of two helical coils having at their junction a dripper.
